CLAIM

The ornamental design for a gasket for lens making, as shown and described.

DESCRIPTION

FIG. 1 is a perspective view of my improved design for a gasket for lens making.

FIG. 2 is a front elevation view thereof.

FIG. 3 is a top plan view thereof.

FIG. 4 is a bottom plan view thereof.

FIG. 5 is a side elevation view thereof, the opposite side of which is a mirror image.

FIG. 6 is a cross-section view thereof taken along lines 6—6 in FIG. 2; and,

FIG. 7 is a cross-section view thereof taken along lines 7—7 in FIG. 3.
